UNITED STATES PATENT OFFICE.

STANLEY E. MARTIN, OF BLOOM, KANSAS.

WINDMILL-POWER ENGINE.

1,394,104.

Specification of Letters Patent.

Patented Oct. 18, 1921.

Application filed June 21, 1918. Serial No. 241,185.

To all whom it may concern:

Be it known that I, STANLEY E. MARTIN, a citizen of the United States, and a resident of Bloom, in the county of Ford and 5 State of Kansas, have invented certain new and useful Improvements in a Windmill-Power Engine, of which the following is a specification.

This invention relates to an engine structure adapted for use in connection with an 10 ordinary windmill, commonly used upon farms for pumping water and an object of the invention is to provide an engine structure adapted for connection with the operating 15 rod of a windmill, for transferring the longitudinal or reciprocatory movement of this rod into rotary movement, whereby the power may be utilized for operating various machines, such as washing machines, churns, 20 wood saws or analogous machines.

More specifically, the invention comprehends the provision of an engine structure comprising a relatively large gear, to which a coupling rod is adjustably connected, 25 which coupling rod is in turn connected to the reciprocatory operating rod of a windmill structure for rotating the gear by the vertical reciprocatory movement of the rod and also to provide a power shaft which is 30 operatively connected, by means of a pinion to the relatively large gear, and carries a suitable balance wheel and pulley, from which latter power may be transmitted by means of an ordinary belt to any desired 35 machine.

A further object of the invention is to provide a coupling member, by means of which the vertically reciprocatory rod of the windmill may be connected to the engine structure 40 independently of connection with the pump rod, of an ordinary water pump, or so that it may be connected to both the engine and the pump rod for operating the engine and pump synchronously.

Other objects of the invention will appear 45 in the following detailed description, taken in connection with the accompanying drawings, forming a part of this specification, and in which drawings:

Figure 1 is a side elevation of the improved engine showing the same connected to the ordinary water pump used in connection with windmills.

Fig. 2 is an end elevation of the pump 50 structure and its connection with the vertically reciprocable rod of the windmill.

Fig. 3 is a top plan of the engine structure showing the pump in cross section.

Fig. 4 is a detail view partially in section of the coupling for connecting the connecting rod of the engine structure to the vertically reciprocable rod of the windmill. 60

Fig. 5 is a horizontal section on the line 5-5 of Fig. 4.

Referring more particularly to the drawings, A indicates the ordinary vertically reciprocable rod of an ordinary windmill structure, and B indicates the usual pump employed in connection with windmills for pumping water, the pump rod C of which is 70 connected to the vertically reciprocable rod A by means of a coupling generally indicated by the letter 1. The coupling 1 is formed upon the lower end of the rod A, and has a laterally offset vertical socketed portion 2 which receives therein the upper end of the rod C and to which the rod C is connected by means of a bolt 3 for reciprocating the pump rod C by the reciprocation of the windmill rod A for operating the pump 80 to pump water. The pump B has the usual type of handle D, by means of which the pump may be manually operated if desired. 85

The coupling 1 has a transversely extending arm 5 formed integrally thereon which arm extends laterally from the rod A in the direction opposite to the coupling 2 as clearly shown in Figs. 2 and 4 of the drawings. The connecting arm 6 of the engine structure has a collar 7 upon its upper end, 90 which collar fits upon the transverse extension 5 and is held thereon against longitudinal movement by means of a pin 8 which extends through the extension 5 and a second pin 9 which also extends diametrically 95 through the extension 5 and engages the inner end of the collar 7. The connecting arm 6 has its lower end curved as shown at 8' and adjustably connected, by means of a bolt 9' to one of the spokes 10 of a relatively 100 large gear 11. The spoke 10 is provided with a plurality of spaced openings 12 to permit adjustment of the connection between the connecting rod 6 and the spokes toward or from the axis of the gear 11. 105

The gear 11 is mounted upon a shaft 13 supported by suitable bearings 14 that are mounted upon the supporting frame 15 of the engine structure. The supporting frame 15 of the engine structure is clamped to the 110 casing of the pump B by suitable clamps 16 and is bolted to the platform of the pump

structure by bolts which extend through the lateral extending flanges 17 formed upon the lower edges of the supporting casing 15. The gear 11, meshes with a pinion 18 which 5 pinion is mounted upon a shaft 19. The shaft 19 is rotatably supported by suitable bearings 20 which are also carried by the pump supporting casing or structure 15. A balance or fly wheel 21 is mounted upon one 10 end of the shaft 19 and a cone pulley 22 is mounted upon the opposite end of the shaft. The cone pulley is provided for transmitting power from the shaft 19 to any suitable type 15 of machines such as a washing machine, rotary churn, wood saws, or the like for operating the said machines by power obtained from an ordinary windmill or propeller.

If it is so desired, the pump and engine may both be operated simultaneously, by 20 connecting the pump rod C with the coupling 1, at the same time connecting the connecting rod 6 to the transverse arm 5, or if it is desired to operate the engine, independently of operation of the pump, the 25 bolt 3 may be removed, and the pump rod C disconnected from the coupling 1, which will allow the rod A to reciprocate vertically, by the rotation of the wind wheel, for operating the engine independently of operation of the pump.

Changes in details may be made without departing from the spirit of the invention, but:

I claim:

35 1. In a device for operating machines by windmill power, the combination with an ordinary vertically reciprocable operating rod of a windmill, an ordinary windmill pump, of power transmitting structure including a 40 relatively large gear, a connecting rod adjustably connected to said gear, a coupling upon the lower end of said vertically reciprocable rod and provided with a transverse extension adapted for detachable connection with 45 said connecting rod to rotate the gear upon

reciprocation of the vertically reciprocable rod and a power take off member carried by said structure.

2. In a device for operating machines by windmill power, the combination with an ordinary vertically reciprocable operating rod of a windmill, an ordinary windmill pump, of power transmitting structure including a relatively large gear, a connecting rod adjustably connected to said gear, a coupling upon the lower end of said vertically reciprocable rod and provided with a transverse extension adapted for detachable connection with said connecting rod to rotate the gear upon reciprocation of the vertically reciprocable rod, said power transmitting structure including a power shaft, means operatively connecting said power shaft to said gear for rotating the power shaft by rotation of the gear and a power take off device carried by the power shaft.

3. In a device for operating machines by windmill power, the combination with an ordinary vertically reciprocable operating rod of a windmill, an ordinary windmill pump, of a power transmitting structure including a relatively large gear, a connecting rod adjustably connected to said gear, a coupling upon the lower end of said vertically reciprocable rod and provided with a transverse extension adapted for detachable connection with said connecting rod to rotate the gear upon reciprocation of the vertically reciprocable rod, said power transmitting structure including a power shaft, means operatively connecting said power shaft to said gear for rotating the power shaft by rotation of the gear, said coupling embodying means whereby the pump and engine may be operated synchronously upon reciprocation of the vertically reciprocable rod or independently of each other and a power take off device carried by said power shaft.

STANLEY E. MARTIN.
